FLAT PIECE LAUNDRY RACK

Merton A. Pocock, Minneapolis, Minn.

Application May 6, 1953, Serial No. 353,265

2 Claims. (Cl. 38—143)

1

My invention relates to racks for laundry flat pieces and is in the nature of an improvement upon the structure disclosed in Patent 1,836,938.

The primary object of my invention is the provision of a device of the class above described wherein forward swinging movements of the drop arms are definitely limited.

A still further object of my invention is the provision of novel means for applying frictional braking action to the drop arms.

A still further object of my invention is the provision of a device of the class immediately above described which is simple in construction, inexpensive to produce, easy to adjust, and extremely durable in use.

Referring to the drawings, wherein like characters indicate like parts throughout the several views:

Fig. 1 is a view in front elevation of my novel structure;

Fig. 2 is an enlarged fragmentary view partly in section and partly in plan taken substantially on the line 2—2 of Fig. 1;

Fig. 3 is an enlarged view partly in vertical section and partly in elevation taken on the line 3—3 of Fig. 1;

Fig. 4 is a view in side elevation of my novel structure; and

Fig. 5 is an enlarged fragmentary sectional view taken substantially on the line 5—5 of Fig. 4.

Referring with greater particularity to the drawings, the numeral 1 indicates in its entirety a frame made up of a pair of generally H-shaped laterally spaced side frame members 2 which are joined together adjacent their lower end portions by tie rods 3 and adjacent their upper end portions by tie rods 4. Depending legs 5 are rendered mobile on floor X by means of casters 6. Projecting upwardly from the rear end portions of the frame members 2, preferably and as shown above the transverse connecting members 7, are legs 8. Opposed trunnions 9 of a windlass, identified in its entirety by the numeral 11 and including a pair of diametrically opposed parallel pipes 12 non-rotatably mounted in opposite end portions of a pair of arms 13, are journaled for rotation on a horizontal plane in the upper end portions of the legs 8. As shown, the arms 13 are rigidly connected at their centers to the trunnions 9. As shown in Fig. 4, the spaced members 12 afford supporting members for flat pieces A being fed thereonto by the operator as they come from flat piece spreaders and the like.

Projecting upwardly from the forward portion of the frame 1 are legs 14 which, at their upper

2

end portions, define upwardly opening sockets 15 for the reception of the stem portions 16 of a pair of opposed bearings 17. A pair of drop arms 19 each has a laterally projecting horizontal trunnion 20 receivable in the aligned openings 21 of the bearings 17. An inner connecting rod 22 connects the axial portions of the drop arms 19, whereas connecting rod 23 connects the radially offset free end portions of said arms 19.

10 As shown, friction washers 24 are interposed between the bearings 17 and the adjacent surfaces of the drop arms 19. For the purpose of varying the frictional relationship between the drop arms 19 and the bearings 17, through the

15 medium of the friction washers 24, it will be noted that the tie rod 4 on the upper end of the leg 14 passes through aligned openings in the socket-forming portions 15 of the legs 14 and through an alignable opening 25 in the stem portions 16

20 of the bearings 17. The opposite ends of said tie rod 4 are threaded, as at 26, to receive outer clamping nuts 27 and inner locking nuts 28. With this structure it is obvious that tightening of the clamping nuts 27 will cause the desired amount of friction to be exerted upon the drop arms 19 by the bearings 17 through the medium of the friction washers 24. Tightening of the

25 locking nuts 28 in the opposite direction will preserve said adjusted frictional relationship. This frictional engagement is highly desirable in moving of the drop arms 19 from the full line to the dotted line position of Fig. 4, and to prevent harsh impact between the drop arms 19 and the underlying tie rod 4. For the purpose of lim-

30 iting forward swinging movements of the drop arms 19 between the vertical and horizontal plane of the axis of swinging movements thereof, the bearings 17 are formed to provide laterally offset lugs 29 which engage the drop arms 19 and pre-

35 vent forward movement beyond the full line position of Fig. 4. By this means, accidental forward dropping movements of the arms 19, with the consequent depositing of the forward end portion of the flat piece A upon the floor X is pre-

40 cluded. The functions of this apparatus in its various adjusted positions is fully explained in said Patent 1,836,938, above referred to.

My invention has been thoroughly tested and found to be completely satisfactory for the accomplishment of the above objects, and while I have disclosed a preferred embodiment thereof, I wish it to be understood that my invention is capable of specific modification without departure from the scope and spirit of the appended claims.

What I claim is:

1. A rack of the class described comprising a frame including a pair of spaced side frame members and tie rods connecting said side frame members, said frame members each having spaced upwardly projecting forward and rearward legs, a windlass extending between the upper ends of said rear legs and journaled for rotation therein, said forward legs terminating below the plane of the rear legs and each thereof defining upwardly opening socket portions, a pair of opposed bearings having depending stem portions receivable in said sockets, said stem portions and sockets having aligned apertures through which opposite ends of an adjacent one of said tie rods project whereby to removably anchor said stems in said sockets, a pair of drop arms having laterally projecting trunnions at their inner ends receivable one each within said bearings for limited rotary movements on a common horizontal axis, inner and outer connecting rods joining respectively the inner and outer end portions of said

drop arms, friction washers interposed between said bearing and the adjacent side of each of said drop arms, and a clamping nut on one end of the tie rod passing through the upper ends of said forward legs and the stems on said bearing, adjustment of said clamping nut varying the frictional relationship between said bearings and drop arms through said friction washers.

2. The structure defined in claim 1 in which said bearings are provided with laterally offset stop lugs engaging said drop arms whereby to positively limit forward swinging movements thereof between the vertical and horizontal plane of the axis of swinging movement thereof.
